UNITED STATES PATENT OFFICE.

HAROLD G. MEADOWS, OF BUFFALO, NEW YORK, ASSIGNOR TO JOSEPH G. DUDLEY, OF BUFFALO, NEW YORK.

BAR FOR REINFORCED CONCRETE CONSTRUCTION.

1,107,434.

Specification of Letters Patent. Patented Aug. 18, 1914.

Application filed December 19, 1910. Serial No. 598,091.

To all whom it may concern:

Be it known that I, HAROLD G. MEADOWS, of the city of Buffalo, in the county of Erie and State of New York, have invented certain new and useful Improvements in Bars for Reinforced Concrete Construction; and I do hereby declare the following to be a full, clear, and exact description of the same, reference being had to the accompanying drawings, forming a part of this specification, and to the reference-numerals marked thereon.

My present invention relates to bars for reinforced concrete construction and has for its object to provide a construction which will make an ideal bond with the concrete to resist stress from any direction, and one which may be readily and cheaply manufactured by the use of rolls and which is ready for use when it leaves the rolls. In providing a bar of this nature, it is necessary to consider not only the surface of the bar itself, but also the surface of the concrete in contact therewith and the action of the concrete when being poured around the bar.

It is well known that concrete will not flow into every little hole or pocket that may be made in the surface of the bar, but may be kept out by air and water entrained in the concrete and also it will be noted that concrete itself is not perfectly fluid. Therefore, in order to obtain a reliable bond between the metal and the concrete, it is necessary to have the spaces between the ribs on the surface of the bar of substantial size, to have the ribs that outline the spaces of substantial dimension, and to have the surface of the concrete that is in contact with the bar broken in no way other than is absolutely necessary to make the bond. So far as the manufacture of the bar is concerned, it is necessary that the texture of the metal forming the bar should be as nearly as possible homogeneous throughout, and to obtain this condition, sudden changes in cross sectional area should be reduced to a minimum, for, if in rolling the bar, the work required to form the ribs, or projections, as the case may be, changes suddenly as the bar passes through the rolls, owing to change in cross sectional area, unequal strains in the material will be set up at these points of change. In the attempts to fulfil these conditions the bars heretofore produced have, as a general rule, been pro-

vided with too great a number of ribs and intervening pockets, thereby breaking up the concrete surface in contact with the bar unduly, and either utilizing too large per cent. of the metal in forming the ribs, or having the ribs too small and too delicate for practical manufacture and use. This form of construction also calls for rolls whose surfaces are cut up to such an extent that they are not only expensive to make but also very short lived, thereby entailing an excessive initial expense and decreased output due to frequent changes. It is also desirable that the arrangement of the ribs or projecting portions of the bar be symmetrical with reference to the longitudinal axis, and so arranged as to resist a pull or twist from any direction equally on opposite sides thereof.

With these objects in view, I have produced the bar shown in the accompanying drawings, which is characterized by having V-shaped ribs with substantial dimensions formed on two adjacent surfaces of the bar, the apexes of the V's being arranged at the meeting point of the two surfaces and the apexes of the adjacent V shaped ribs thus formed extending alternately in opposite directions, longitudinally of the bar. I prefer that the V shaped ribs on the other pair of adjacent faces of the bar be similarly arranged with reference to each other, and also diametrically opposite the first ones mentioned, as will be hereinafter more fully described.

In the drawings:—Figure 1 is a perspective view of a steel member for concrete bar constructed in accordance with my invention. Fig. 2 is a view looking down upon the two adjacent faces made by the same roll. Fig. 3 is a side elevation. Fig. 4 is a cross sectional view on the line x—x of Fig. 3. Fig. 5 is a developed view showing the ribs and the manner in which they coöperate with the concrete in contact therewith and between. Fig. 6 is a similar view showing construction produced if the rolls should creep, due to wear in the wabblers or coupling boxes while the bars are being rolled.

Similar reference numerals in the several figures indicate similar parts.

I prefer to employ my invention in connection with bars which are rectangular in cross section and these are formed as usual by rolls, the passes of which are rectangular

116

and the projections or ribs are formed by grooves cut in the faces of these rectangular passes and at an obtuse angle with the circumference of the rolls. The bar as shown in Figs. 1 and 2, and indicated by A, is preferably rectangular in cross section, and has upon each of its faces, 1, 2, 3 and 4, a plurality of ribs *a* and *b* extending above the surface of the bar and at an angle to its longitudinal axis, the adjacent ribs on each plain face extending diagonally in opposite directions, so that the spaces between are of substantial area. The two adjacent surfaces 1 and 2, are preferably formed by the same roll, (as shown in Fig. 2), and the ribs *a* on these faces meet at the edge, angle or corner of the bar. Each succeeding V shaped rib thus formed extends in the opposite direction from the preceding one. The ribs *b* on the opposite side of the bar, which are formed by the other one of the pair of rolls, are preferably arranged directly opposite the ribs on the surfaces 1 and 2, and the ends of the ribs *b* on the adjacent surfaces 3 and 4, preferably meet the ends of those on the surfaces 1 and 2, so that at each corner or angle there are presented oppositely disposed V shaped ribs, making the bars as a whole symmetrical, and the spaces between the ribs and with which the concrete is in contact, substantially the shape shown in Fig. 5. From an examination of this figure it will be noted that the concrete is in contact with the flat surfaces of the bar in unbroken circumferential zones or bands which have corrugated or zigzag edges engaging the ribs. I prefer this arrangement of the ribs for the reason that when the bar is pulled in either direction the sides of the unbroken circumferential bands of concrete are pinched or compressed into the troughs of the V's on all sides of the bar and the angular arrangement of the ribs resists the tendency of the bar to twist in the concrete. This arrangement of the V-shaped ribs or projections extending over the corners of the bars, and arranged as shown, also insures the production of efficient angular ribs, etc., even if the rolls or bars should creep in rolling or the metal should flow unevenly in or on opposite rolls, the construction produced under these circumstances being substantially like that shown in the developed view Fig. 6. In this instance, the arrangement of the ribs is such as to prevent the relative movement of the bar and concrete through forces exerted in any direction while the areas of concrete in contact with the surface of the bar are large, and this though produced by the improper action of the rolls accentuates the fact that not only is the intended construction of the bar as a whole illustrated in the other figures of the drawing, advantageous, but that the features of construction are such that good re-

sults are obtained even when the manufacture is defective for reasons beyond the control of the operator.

The bar constructed as described possesses the following features of importance: It is symmetrical with reference to its longitudinal axis and thus produces an equal strain on both sides of the bar and the concrete envelop. Its surface is formed of substantial diameters spaced a substantial distance apart and it will break up the concrete sufficiently for the maintenance of a perfect bond between the concrete and bar. The ribs on the bar are so arranged that they will be made gradually and the metal distributed along some considerable proportion of the length of the bar, thereby minimizing the setting up of strains in the metal, due to a sudden variation in the section of the bar and this is contributed to by the fact that the sides of the ribs form an obtuse angle with the surface of the bar in order to allow the metal to flow in the grooves that form the ribs and also that there are no pockets formed by the ribs that will catch the water and air entrained in the concrete to the exclusion of the concrete itself and therefore a more firm joint will be provided with the two materials.

It will be noted that with the V-shaped ribs of substantial dimension, spaced and arranged as shown in the bar, these ribs form a practically continuous zigzag rib of uniform cross section around the bar which is only broken at the two opposite corners that correspond with the parting between the rolls by which the bar is formed, as shown particularly in Fig. 3.

The specific form of the cross section of the ribs, that is to say, whether round, angular or otherwise is not of great moment, but it is desirable that the sides be inclined to the plane of the surface of the bar in order to facilitate the operation of rolling them. It is also desirable that a cross section of the bar, as a whole, be angular and preferably rectangular in order to reduce as much as possible the liability of a relative twisting between the bar and the concrete, but the advantageous results of my construction would be obtained in a measure even if the bar were round or did not have the sharp corners, and in such a bar with rounded edges the two adjacent surfaces, corresponding to the surface indicated by 1 and 2 in the angular bar, will be those on opposite sides of lines drawn through the apexes of the V, or other shaped ribs.

It will be understood that the term V shaped, as applied to the ribs, is only approximately descriptive and is not intended to limit the construction to one in which the ends of the ribs necessarily merge at an acute angle, but merely to one in which the same results are obtained in respect to the

wedging action, which resists the relatively longitudinal movement of the bar and concrete. In the case of bars which are not definitely angular in cross section, the term 5 sides may be considered to apply to the portions of the bar immediately adjacent to the line extending longitudinally of the bar and passing through the apexes of the V's; in other words, constituting the part which, in 10 the angular formation of the bar shown, is formed by one of the rolls.

I claim as my invention:

1. A bar for reinforced concrete having two series of substantially V-shaped ribs 15 substantially diametrically opposite each other, the apexes of the longitudinally adjacent V's, projecting in opposite directions longitudinally of the bar and the ribs at said apexes being wholly separated a considerable distance from each other.

2. A bar for reinforced concrete having two series of similar V-shaped ribs arranged substantially opposite each other, the apexes 20 of the longitudinally adjacent V's in each series extending alternately in opposite directions longitudinally of the bar and the ribs at said apexes being wholly separated a considerable distance from each other.

3. A bar for reinforced concrete, angular 25 in cross-section and having two series of ribs on each face, occurring alternately, those of one series being inclined in opposite direction to those of the other series, longitudinally in respect to the axis of the 35 bar, the corresponding ribs extending in opposite directions on adjacent faces, meeting at the edges, angles or corners of the bar, and being wholly separated at this point a considerable distance from the meeting 40 points of the next adjacent pair of ribs.

4. A bar for reinforced concrete, having a plurality of ribs forming bands extending 45 around it and inclined alternately in opposite directions relatively to the longitudinal axis thereof, forming a series of V-shaped projections, the apexes of the V's of adjacent bands extending longitudinally of the

bar and in opposite directions and the ribs of each band being wholly separated a considerable distance from each other.

50

5. A bar for reinforced concrete, having a plurality of ribs extending around it in the nature of zigzag bands, each band composed of a series of straight ribs meeting, and changing directions at the corner of the 55 bar, said bands being a considerable distance apart at their nearest points, and each having the apexes of the V's, formed at the corners of the bar by the meeting of the ribs, point in opposite direction, longitudinally of 60 the bar, to that of the V at the corresponding corner in the next adjacent band.

6. A bar for reinforced concrete angular in cross section having a series of substantially V-shaped ribs between each pair of 65 adjacent faces thereof, the apex of each V projecting longitudinally of the bar in an opposite direction to, and the ribs being wholly separated a considerable distance from, the apex of the next adjacent V on 70 the same pair of faces.

7. A bar for reinforced concrete, angular in cross section, and having on each face a row of narrow ribs extending across the face in a plane inclined relative to the longitudinal axis of the bar, the ribs in said row being divided into two series, those of one series being inclined in opposite directions to, occurring alternately with, and being separated a considerable distance from 80 those of the other series; all ribs being so arranged that each will extend at an angle to and its ends will approximate the ends of one of the other series on each of the next adjacent faces, forming a series of zig-zag 85 bands around the bar, each band composed of a plurality of straight members that meet, or nearly meet, and change direction at each corner of the bar.
